PROPELLER CONSTRUCTION HAVING
INTEGRAL HUB RESERVOIR

Arthur N. Allen, Jr., Wethersfield, Conn., assignor
to United Aircraft Corporation, East Hartford,
Conn., a corporation of Delaware

Application April 8, 1950, Serial No. 154,857

6 Claims. (Cl. 170—160.33)

1

This invention relates to variable pitch propellers and more specifically to an improved hub construction therefor.

It is an object of this invention to provide a propeller hub construction wherein an integral fluid reservoir is provided in the hub.

A further object of this invention is to provide an improved hub for a variable pitch propeller wherein the space between the propeller blade sockets is completely enclosed so as to form an integral fluid reservoir in the hub.

Another object of this invention is to provide an improved hydraulically operated variable pitch propeller construction including a hub having the blade sockets interconnected by integral closure means to form wall portions for a self-contained chamber and a closure member forming an axially spaced wall of the chamber whereby operating units for propeller operation and pitch variation are carried by the closure member and housed adjacent to the reservoir.

A still further object of this invention is to provide a closure member for a self-contained fluid chamber in a propeller hub construction of the type described which carries hydraulic propeller operating units and fluid passages which provide fluid communication with the main bulb portion and pitch changing units when closure member is engageably positioned thereon.

These and other objects will become readily apparent from the following detailed description of the drawings in which:

Fig. 1 is a front view of the propeller hub construction of this invention with only a portion of the propeller blades shown for convenience.

Fig. 2 is a cross sectional view taken along the line 2—2 of Fig. 1 and illustrating the hub including its associated, integral propeller operating mechanisms.

Fig. 3 is a rear view of the hub with its rear closure member removed.

Fig. 4 is a cross sectional view taken along the line 4—4 of Fig. 3.

Fig. 5 is a cross sectional view taken along the line 5—5 of Fig. 2 and illustrating the positions of the major propeller pitch control and operating components carried by the hub rear closure member.

Fig. 6 is a detail cross sectional view taken along the line 6—6 of Fig. 5 and illustrating the scavenging pump mounting and associated drive units assembled on the hub rear closure member.

Fig. 7 is a detail cross sectional view taken along the line 7—7 of Fig. 5 and illustrating the mounting of another of the propeller pump units.

2

Fig. 8 is a detail cross sectional view taken along the line 8—8 of Fig. 5 illustrating the passages leading from the main pump units to the propeller distributor valve.

Fig. 9 is a cross sectional view taken along the line 9—9 of Fig. 5 illustrating a passage from the main pumping system leading to the high pressure relief valve.

Fig. 10 is a detail cross sectional view taken along the line 10—10 of Fig. 5 showing the high pressure relief valve including the passages leading thereto and therefrom.

Figs. 11 and 12 are cross sectional views through 11—11 and 12—12 of Fig. 5 showing oil passages leading from the distributor valve to the passages of the header ring which supplies the pitch change mechanism with hydraulic fluid.

Fig. 13 is a cross sectional view through the line 13—13 of Fig. 5 indicating the sump relief valve.

Generally, the propeller and hub construction as illustrated and described in detail herein comprises a plurality of hydraulically operated variable pitch propeller blades carried within the hub. The blades contain hydraulic vane motors which respond to fluid pressure in a manner that will become apparent hereinafter.

Referring to Figs. 1 and 2, a hub 20 is shown having a plurality of propeller blades 22 mounted for pitch changing movement therein. As seen better in Fig. 2, the hub 20 is positioned on its drive shaft by means of a front cone 24 and a rear cone which is not shown. The hub 20 comprises a completely integral main portion 30 having blade receiving sockets 32 and an interblade or intersocket webbing 34 which along with the sockets terminates in an annular shroud 36 which is spaced from the hub axis so as to form walls of a continuous annular chamber or sump 40. The shroud 36, while forming a portion of the chamber 40, is tapered toward the forward end of the entire assembly whereby it is readily adaptable to provide a continuing streamline surface for a propeller spinner, a portion of which is illustrated in phantom at 44.

A more clear picture of the main hub portion is obtained by reference to Figs. 3 and 4 which illustrate the previously mentioned hub main portion 30 including its sockets 32, inter-socket web 34 and shroud 36. The main portion 30 also includes a cylindrical portion 56 which surrounds the propeller drive shaft and has splines 57 on its internal periphery for engagement with said propeller drive shaft.

A closure member or plate 50 is provided for

sealing engagement with the hub main portion 30 to completely enclose the sump 40 and provide a fluid tight chamber which is integral with the propeller hub and which can be filled with fluid by removing the plugs 41. Seals 51 are provided between the shroud 36 and the closure member 50 and seal 51a is provided between the main hub portion 30 and closure member 50 adjacent the internal periphery of the hub portion 30. As will become more clearly apparent hereinafter, the plate 50, while serving to close off the sump 40, serves to carry the major pump and controlling units required for variable pitch operation so that these various units can be separately assembled on the plate 50 and subsequently readily fitted to the hub main portion 30 with great facility. Also, as will be seen hereinafter, the plate 50 includes the necessary fluid passages therein which place the various control units in fluid communication with the main portion of the hub and pitch changing units merely by placing the plate 50 and its accessories in engaging position with the main hub portion 30 and its integral shroud 36.

The closure plate 50 is mounted by studs 52a (Fig. 3) which are located within the ears 52 on the aft end of the shroud 36 of the main hub portion 30 and screws 400 at its inner periphery as shown on Figs. 5, 6 and 7.

In order to synchronize the pitch changing movement of all of the blades a bevel gear 210 is provided which engages gear segments 212 integral with the movable portion 178 of the blade vane motors.

In order to provide mechanical pitch stops for the propeller blades a pair of stop rings 220 each having two lugs are splined to an extension 222 formed on the blade synchronizing gear 210. Cooperating stops are provided on a member 224 which is in turn splined with the main hub portion 30.

The blade synchronizing gear 210 further carries a depending ring gear 226 which drives a blade follow-up shaft 230. The follow-up shaft 230 is fixed for rotation within the main hub portion 30 and carries at its aft end a driving gear 232. Hence, upon pitch changing movements of the propeller blades the shaft 230 and its gear 232 will, by means of a connector gear 234, rotate a valve return gear 236 which has a splined connection to a valve reciprocating member 240. Thus, pitch changing movements of the propellers will, by means of the follow-up mechanism and a worm connection described below, cause the distributor valve 90 to be repositioned.

In order to operate the previously mentioned pumps and to control the pilot valve 90, a controlling unit 258, illustrated in phantom in Fig. 2, is fixed to the adjacent power plant housing and contains governing units and a planetary gear system which does not form a specific part of this invention and hence will not be described in detail. It will suffice, however, to mention that during propeller rotation the gear 78, which has fixed thereto another gear 252 is normally held stationary by means of interconnections with units in the control housing so that the pump units fixed to the closure member 50 will be operated as they revolve around the gear 78. The entire control assembly is further supported on the main hub portion 30 by ball bearings 254 so that the hub may rotate while the control unit may remain stationary.

A distributor valve drive gear assembly 256 is also provided and has at its forward end a gear

258 and at its aft end a gear 260. The gear is operatively connected to the planetary gear system within the control housing in such a manner that, for an on-speed condition of the propeller, gear 256 will normally rotate in phase with the propeller. Therefore, the gear 258, which is connected to a valve operating gear 262, will maintain a position relatively fixed to the propeller. Gear 262, restrained from axial movement by its mounting, has a screw thread connection with valve reciprocating element 240. It is apparent therefore that when there is no pitch change demand or response gear 236 is held stationary and thus the screw member 240 will maintain valve member 90 in a fixed position. However, in the event that a pitch change is called for by control unit or governor in the housing 250 the planetary system therein will cause the valve drive assembly 256 through its gear 260 to change its phase relation with the propeller and hub. This relative rotation will cause the gear 258 to rotate the gear 262 and through the worm connection 264 cause the valve 90 to move along its axis and thereby control pitch changing movements of the propeller blades. Upon such movement of the blades the follow-up mechanism described will tend to reposition the valve in a neutral position.

The arrangement of the various pitch operating and control units which are carried by the closure member or plate 50 is best seen in Fig. 5. These units comprise a high pressure pump 60 and a stand-by high pressure pump 62. The outlets of these pumps are connected to the pilot valve 90 for proper high pressure fluid distribution to the pitch change units 178 (Fig. 2) and to a high pressure relief valve 64 which limits the high operating pressure at a desirable level by dumping excessive fluid back into the sump 40. A scavenge pump 66 is also provided which picks up fluid that may accumulate in the chamber 68 (see also Fig. 2) located immediately aft of the closure member 50. It will suffice at this point to mention that chamber 68 is at atmospheric pressure. The chamber 68 is defined by the closure plate 50 and a backing plate 69 which is attached to the hub by means of the studs 52a (Fig. 4) so as to engage the outer periphery of the closure plate 50 in the manner shown in Fig. 4. The studs 52a pass through a plurality of bosses (not shown) spaced adjacent the periphery of the closure plate 50 so that the backing plate 69 mates accurately with the plate 50 where the studs are located. A slight clearance may exist, then, between the adjacent faces of the plates 50 and 69 in the peripheral spaces between adjacent studs.

The scavenge pump 66, as better seen in Fig. 6 fits into a cavity in the closure member 50 and takes in fluid from the chamber 68 via an inlet passage 70 and discharges the fluid into the pressurized sump 40 via an outlet passage 72. The passages 70 and 72 are formed within the plate member 50. The pressure in the sump 40 is controlled by a relief valve 402 (Fig. 13) also mounted in plate 50. Excess of pressurized fluid or oil is thereby relieved from the sump to the atmospheric chamber 68. An idle gear 74 journaled in the closure member 50 provides a driving connection between the scavenge pump drive gear 76 and a normally stationary gear 78. The idle gear 74 includes a hollow shaft 80 which receives fluid under sump pressure from a passage 82 to provide a bleed type pressure lubrication of its bearings and adjacent gear mechanism. Such

lubricating fluid forms part of the fluid accumulation in the chamber 68. A lubricating valve 83 (Fig. 5) provides further lubrication to the other gears located within the chamber 68.

Fig. 7 illustrates one of the high pressure pumps which has its driving gear 86 connected to the previously mentioned normally stationary gear 78. Fluid enters the pump from the pressurized sump 40 through an inlet passage 88 and discharges this high pressure fluid into high pressure passages leading to the distributor valve 90 (Fig. 8) for proper apportionment of the fluid to the propeller pitch changing mechanism. As seen in Fig. 8, the distributor valve receives fluid from the main high pressure pump 60 via a passage 92 and also from the stand-by pump 62 via a passage 94. Although both pumps 60 and 62 are continuously operating, when the distributor valve 90 is in its neutral position or when the blades are responding sufficiently rapid to small controlling movements of the distributor valve 90, fluid from the stand-by pump, which enters the valve by means of the passage 94, flows through the pump housing passage 96, past the valve land 98 and through the hole 100. The fluid is then discharged through the core of the valve 90 into the pressurized sump 40. In this manner, only when greater volume is necessary, does the discharge from the stand-by pump come into play. In other words, the output of both pumps 60 and 62 will be utilized for pitch change when rapid movements are called for by the valve mechanism 90 previously described.

As seen in Fig. 9, the high pressure pump 60 is connected to a passage 104 which in turn leads 35 to a passage 106, seen in Fig. 10, communicating with the relief valve 64. The relief valve 64 includes a valve member 108 which has its upper end operatively connected to a plurality of Belleville washers 110. In this way the valve member 108 will have a snap action so that it will pop open and close at a rapid speed so as to relieve fluid pressure from the passage 106 out through the passage 112 and eventually to the pressurized sump 40.

Returning to Fig. 2, the distributor valve 90 is also in communication with a stand-by check valve 120. The purpose of this valve is to bring into operation the additional capacity of the stand-by pump 62. Thus, when movements of 50 the distributor valve 90 are relatively large (indicating a lack of response in propeller pitch change) so that additional fluid is necessary for adequate propeller pitch variation, the fluid from the stand-by pump will, instead of being dumped into the sump 40 as previously described be forced through the passage 122 leading from the valve 90 into the check valve 120, then past the ball check and via the passage 124 back to the distributor valve through the passage 126 located 60 in the distributor valve housing. This passage 126, which is also seen in Fig. 8, it will be noted, provides additional fluid to the valve simultaneously with the fluid coming from the main pump 60 via the passage 92.

In order to follow the high pressure flow from the distributor valve 90, which flow is used to vary the pitch of propeller blades, it is best to refer to Figs. 11 and 12. Thus, for one pitch changing direction fluid under pressure is passed 70 via the passage 130 through the passages 132 and 134 to an opening 136 which leads to an annular transfer passage 138 in a header ring 140 which ring in turn distributes fluid under pressure to the pitch changing motors located in each of the 75

propeller blades. For pitch changing movement in the other direction (Fig. 12) fluid under pressure from the distributor valve 90 passes to a passage 144 which is spaced from the previously mentioned passage 130 circumferentially about the axis of distributor valve 90. Fluid under pressure from the passage 144 then flows via the passages 146, 148 and the port 150 into the second annular transfer passage 152 in the header ring 140 from whence it is passed to each of the pitch changing motors in the propeller blades to vary the pitch in another direction.

It will be noted that the high pressure passages 130 and 144 (Figs. 11 and 12) leading from the valve 90 are drilled within the valve housing and have their forward ends plugged with inserts 156. It will be further noted that a fluid tight connection between passages 132 and 134 (Fig. 11) and between passages 146 and 148 (Fig. 12) completed upon positioning of the closure plate 50 upon the rear of the hub portion 30 by means of sleeves 158 and 159 which have a pressed fit into the ports 134 and 148, respectively. Hence the aft extending portions of the sleeves will engage the inner periphery of the seals 160 and also the coupling member 161 which carries the seals whereby a fluid tight high pressure connection is obtained upon installation of the closure plate 50.

The passage of fluid from the header ring 140 is best seen in Fig. 2. As viewed herein, it can be seen that the annular chambers 138 and 152 in the header ring 140 communicate with mating passages in a fluid transfer screw 170 which is located centrally of the stationary portion 174 of a vane motor located within the base of each of the propeller blades 22. The fluid under pressure passes from the transfer screw 170 to either side of the vanes in the motor so that the passages 138 and 152 may alternately serve as pressure or drain conduits. The stationary vane motor portion 174 is held fixed by means of a toothed connection with the main hub portion 30 as indicated at 176. The movable portion 178 of the vane motor is splined at 180 to the inner periphery of the blade shank so that its motion is transmitted to the blade to vary the pitch thereof.

The transfer screw 170 is more fully described and claimed in copending patent application Serial No. 149,545, filed March 14, 1950, by Earl M. Frankland.

Each of the propeller blades 22 is retained within the blade socket 32 by means of a plurality of ball bearings 184 which engage integral races formed on the inner periphery of the blade socket 32 and on the outer periphery of the shank of blade 22. The bearings are inserted through a plurality of holes 186 which are provided in the sides of the sockets 32. In order to preload these bearings a nut 190 is provided at the base of the blade surrounding the bottom of the fluid transfer screw 170 so that the blade 22 may be forced outwardly.

The holes 186 for inserting the ball bearings 184 which are located on the aft side of socket 32 (right side as viewed in Fig. 2) are provided with hollow insert plugs 190 so as to permit fluid communication between the pressurized sump 40 and a second annular chamber 404 adjacent the base of the blades for lubricating purposes. The heads of the plugs 190 are large enough in diameter so that the projections 192 on the forward face of the closure member 50 will retain all of the plugs 190 in position as illustrated. The retaining plugs 196 on the forward side of the socket

32 have overlapping heads so that a clamp 198 bolted to the front of the hub will retain all of the plugs in place by bearing only on one of them as shown.

In order to seal off the second annular chamber at the base of the blades (inasmuch as the fluid therein will be under sump pressure) a cover plate 200 is provided at the forward end of the main hub portion 30 and is connected thereto by means of bolts 202. The propeller retaining nut 10 204 has a sealing engagement with the cover plate 200 and with the header ring 140 by means of the seals 206 and 406. Combined with the sealing elements between the blade sockets 32 of hub 30 the above-mentioned seals serve to completely 15 close off the blade lubricating chamber.

In order to seal the chamber 68 which is at atmospheric pressure a running rubber seal 280 is provided which has a substantially U cross sectional shape and is held fixed against rotation to the control housing 250 by a garter type spring. A spreadable spring steel collar 282 is positioned intermediate the garter spring and the seal 280 so that the spring pressure will tend to spread the free ends of the U shaped seal 280. A pair 25 of depending seal engaging members 284 and 286 straddle the seal 280 and are fixed for rotation with the hub. Any fluid that may pass between the seal 280 and the engaging member 284 will be 30 centrifuged back into the chamber 68 by means of a plurality of holes 288 provided in the seal engaging member 284. Primary sealing, however, is maintained between the seal 280 and the seal 286 so that fluid under atmospheric pressure in the chamber 68 will be held 35 therein against leakage outboard.

In the event a failure of the hydraulic system or other causes which may influence the pitch changing movements of the blades so that the blades tend to move toward a low pitch position while the distributor valve 90 is calling for a high pitch, an automatic pitch lock mechanism is provided. The pitch lock consists of an axially slideable annular cylinder 300 which is located forward of the header ring 140 and is biased in a forward direction by a plurality of coil springs 302. The forward end of the piston 300 has ratchet type teeth which mate at 304 with similar teeth on the blade synchronizing gear 210. During normal operation fluid under pressure in chamber 306 tends to maintain the piston in a disengaged position by forcing it aft against the bias of springs 302. The fluid under pressure for chamber 306 is obtained from the passage 310 which surrounds the follow-up shaft 230 and the passage 312 which is in communication with drain pressure in the central portion 314 of the distributor valve 90. This pressure is maintained at some predetermined value slightly above the pressure existent in the sump 40 by means of a pitch lock relief valve 316 which in its relieving operation dumps excessive fluid directly into the sump 40. In the event that the propeller blades are tending to go toward a low pitch and in responding to a call for high pitch by the distributor valve 90 the passage 312 will be opened to the passage 318 rather than to the drain pressure in the distributor valve so that any pressure existing in the passage 312 will be relieved into the chamber 68 which is at atmospheric pressure. Relief of pressure in this manner will immediately relieve the pressure in the chamber 306 which is acting on the piston 300 so that the springs 302 will cause engagement of the ratchet teeth on the piston 300 and the synchronizing

gear 210. The ratchet teeth mentioned are of such shape that they will permit movement of the blades toward high pitch while they will lock them against movement toward low pitch. Thus, should pressure be restored intermittently or should sufficient pressure be attained to operate the pitch changing mechanism, movement toward high pitch will be immediately attained even though sufficient drain pressure may not have as yet built up to disengage the teeth on the lock piston 300.

The pitch lock system described may be of the type more fully described and claimed in patent application Serial No. 129,082, filed November 23, 1949, by Erle Martin and Thomas Rhines and in patent application Serial No. 128,955, filed November 23, 1949, by John E. Anderson which matured into Patent No. 2,635,702.

Thus, as a result of this invention it is readily apparent that a completely operative propeller unit has been provided which is substantially integral with the unitary rotating hub to form a compact mechanism while providing a self-contained fluid reservoir within the rotating hub.

Also, it is evident that a closure member has been provided to seal off the integral reservoir which closure member upon being positioned provides the necessary communicating passages to the pitch changing mechanisms while further carrying the pitch changing pump and control units.

Further as a result of this invention an integral fluid reservoir has been provided within the propeller hub by utilizing the inter-blade space so that the main hub portion forms a majority of the reservoir walls thereby a single plate-like closure member can be readily attached thereto in operative position without the necessity of numerous assembly steps.

Although only one embodiment of this invention has been illustrated and described herein, it is obvious that various changes and modifications will be made in the arrangement and construction of the various components without departing from the scope of this novel concept.

45 What it is desired to secure by Letters Patent is:

1. In a variable pitch propeller, a unitary hub portion comprising a central member extending along the axis of propeller rotation and adapted 50 to engage a propeller driving shaft, blade receiving sockets extending outwardly from said central member, closure means spanning the space between said sockets, and a shroud coaxially disposed in spaced surrounding relation with said central member and engaging the outer periphery of said closure means to form an annular chamber, a closure member axially spaced from said closure means and engaging said shroud and said central member for sealing said chamber including hydraulic units carried thereby and integral fluid passages therein, propeller blades mounted for pitch changing movements in said sockets and including pitch changing units therein, and passage means carried by said unitary hub portion providing fluid communication between said pitch changing units and said hydraulic units including connecting means providing fluid tight connection between said units.

2. In a variable pitch propeller, a unitary hub 70 member comprising radially extending blade receiving sockets and closure means spanning the space between said sockets thereby forming a wall substantially transversely of the axis of rotation of the hub, said unitary member including a shroud spaced from said axis and extend-

ing along said axis, said shroud engaging said wall, a closure member cooperating with said shroud and axially spaced from said wall forming a first fluid confining chamber within the hub, propeller blades mounted for pitch changing movement within said sockets, said blades terminating at their inboard ends in radially spaced relation with the hub axis thereby forming walls of a second chamber, means engaging said unitary member to enclose said second chamber, pitch changing means for said blades, first passage means in said sockets providing communication between said first and second chambers, control mechanism supported by said closure means for operating said pitch changing means including means for withdrawing fluid from said first chamber, and second passage means carried by said closure means providing fluid communication between said control means and said pitch changing means.

3. In a variable pitch propeller, a hub comprising a central member extending along the axis of propeller rotation and adapted to engage a propeller drive shaft, blade receiving sockets extending radially from said central member, webbing spanning the space between said sockets and forming a wall, an annular shroud extending in an aft direction from adjacent the outer periphery of said webbing and the outer extremities of said sockets, and a closure plate engaging the aft end of said shroud and central member forming a first chamber, blades mounted for pitch changing movement in said sockets with the inner end of the blades radially spaced from said central member forming a second chamber, and passage means in the walls of said sockets providing communication between said chambers.

4. In a variable pitch propeller according to claim 3 including pitch changing fluid motors in the base of said blades, control mechanism carried by said plate and passage means leading to said motors and said control mechanism.

5. In a propeller according to claim 1 having a low pressure chamber communicating with said

5 hydraulic units, said low pressure chamber comprising, a chamber wall section fixed to said hub unit and rotatable with the propeller, a control housing fixed against rotation and located adjacent to said wall section and sealing means engaging said wall section and said fixed control housing.

10 6. In a variable pitch propeller, a hub comprising a central member extending along the axis of propeller rotation and adapted to engage a propeller drive shaft, blade receiving sockets extending radially from said central member, webbing spanning the space between said sockets and forming a wall located in a plane on one side of the center lines of said sockets, an annular shroud having one end located adjacent the outer periphery of said webbing and the outer extremities of said sockets and extending along the axis of propeller rotation, and a closure plate 15 engaging the other end of said shroud and central member, said closure plate being located in a plane on the other side of the center line of said sockets, whereby said central member, said webbing, said shroud and said closure plate form a sump chamber between and in the plane of said sockets and said central member forms a closure for the inner ends of said sockets and separates said sockets from said chamber.
